DIES FOR FORGING CALKING AND YARNING IRONS

Filed Aug. 4, 1925

UNITED STATES PATENT OFFICE.

LEWIS C. BAYLES, OF EASTON, PENNSYLVANIA, AND HOWARD W. MORROW, OF PHILADELPHIA, NEW JERSEY, ASSIGNEES TO INGERSOLL-RAND COMPANY, OF JERSEY CITY, NEW JERSEY, A CORPORATION OF NEW JERSEY.

DIES FOR FORGING CALKING AND YARNING IRONS.

Application filed August 4, 1925. Serial No. 48,016.

This invention relates to calking irons, but more particularly to a device for forming calking irons.

One of the objects of the invention is to prevent excessive lateral displacement of the metal during the breaking down process.

Another object is to combine in a unitary structure, the breaking down, the finishing and edging portions for forming calking irons, and a still further object is to enable calking irons of various dimensions to be formed by a single pair of dies.

Other objects will be in part obvious and in part pointed out hereinafter.

15 The invention consists of the combinations of elements, features of construction and arrangement of parts having the general mode of operation substantially as hereinafter described and more particularly pointed out in the 20 appended claims and illustrated in the accompanying drawings, in which

Figure 1 is a perspective view of a bottom die constructed in accordance with the practice of the invention,

25 Figure 2 is a transverse sectional view through Figure 1 taken on the line 2—2,

Figure 3 is a side view of a calking iron showing the formation of said iron after the initial breaking down operation,

30 Figure 4 is a top plan view of the iron shown in Figure 3,

Figure 5 is a transverse sectional view through Figure 1 on the line 5—5 looking in the direction of the arrows and showing the 35 manner in which the iron is edged,

Figure 6 is a perspective view of the iron illustrating the formation of said iron after the first edging operation,

40 Figure 7 is a transverse sectional view through Figure 1 on the line 7—7 looking in the direction of the arrows illustrating the second or final breaking down operation,

Figure 8 is a top plan view of the iron illustrating the appearance of the iron after the second breaking down operation illustrated in Figure 7,

45 Figure 9 is a view similar to Figure 5 taken on the line 9—9 of Figure 1 showing the second or final edging operation,

50 Figure 10 is a perspective view of the iron after the final edging operation,

Figure 11 is a transverse sectional view

through Figure 1 on the line 11—11 looking in the direction of the arrows illustrating the final forming operation, and

55 Figure 12 is a perspective view of the iron after the final forming operation illustrated in Figure 11.

Referring to the drawings, and more particularly to Figure 1 in which is illustrated a bottom die A comprising various stepped portions for breaking down, forming and edging calking irons or other similar tools. The die A may be secured to a drop hammer or other forging machine in any suitable manner, but preferably remains stationary 60 with respect to such apparatus.

In accordance with the practice of the invention, a prominence or portion B comprising the initial breaking down portion of the die A is formed transversely thereof and is relieved as at C so that only a small portion of a calking iron D may be interposed

65 between said portion B and a reciprocatory top die E at each stroke of said top die E. The portion B is preferably of a length equalling approximately the width of the formed portion of the iron D. After the top die E is again raised the unformed portion F adjacent the broken down or bit portion G of the iron D may be inserted be-

70 tween the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

75 The portion F of the iron D may be inserted between the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

80 The portion F of the iron D may be inserted between the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

85 The portion F of the iron D may be inserted between the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

90 The portion F of the iron D may be inserted between the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

95 The portion F of the iron D may be inserted between the top and bottom dies until approximately the desired length has been broken down. This operation will form the iron D as illustrated in Figures 3 and 4. After the initial breaking down operation, the iron D may be placed edgewise on an edging portion H of the bottom die A and the top die E may then be lowered to form the edges J of the iron D as illustrated in Figure 5.

considerably less than would be the case if the portion K were increased in length. The metal is therefore expanded in a longitudinal direction rather than transversely. After the operation illustrated in Figure 7, the edges J of the iron D will again be corrugated somewhat in the same manner as they were after the first breaking down operation. In order to straighten said edges the iron D may again be placed on the edging portion H of the die as illustrated in Figure 9 and the top die E may be reciprocated to straighten the edges J as illustrated in Figure 10.

15 Additional means are provided for finally forming the bit G to the desired thickness. To this end forming portions O, P, Q and R are formed transversely of the die and are so formed that various degrees of thickness 20 of the bit G may be obtained during the final forming operation, that is, the forming portion Q is slightly higher than the adjacent portion R, and similarly the portion P is slightly higher than the portion Q and the portion O is in turn slightly higher than the portion P. In this instance, the portion O is that portion which will reduce the bit G to a minimum thickness, as illustrated in Figure 25 11. The iron D will then assume the finished form as illustrated in Figure 12. It will be understood that any number of similar forming portions may be included in a die of this type, depending upon the thickness of the iron D required.

30 35 In order to prevent the formation of sharp corners at the juncture of the bit G and the shank of the iron D, the die A is radiused as at S to form a corresponding radius on one side of the iron D. By thus forming a 40 radius on the iron a convenient means is provided for properly locating the iron on the die A for the succeeding operation. The radius on the iron may then be abutted against the radius S of the die A and in this way 45 the iron D is protected against being inserted too far between the top die E and the bottom die A.

50 55 In order to prevent the forming of a similar radius on the back of the bit G at the juncture of said bit and the shank, the top die E preferably overhangs or projects beyond the front edge of the bottom die. In this way, the shank of the iron D is automatically set at an angle to the bit G upon 60 each blow of the die E, the angle thus formed being substantially the desired angle in an iron of this character. If, however, it be desired to still further increase the angle of the bit G to the shank of the iron, the operator may, after the final operation and 65 while the top die E is still in the position indicated in Figure 1, bear down upon the

shank of the tool to form any convenient angle which may be desired.

Although the drawings show the forming faces of the dies A and E parallel with each other, it is to be understood that the faces may taper somewhat to produce a corresponding taper on the iron.

The advantages of this invention reside 70 chiefly in the fact that the expansion of the metal comprising the tool may be regulated, that is to say, instead of breaking down the entire portion comprising the bit G by one blow of the top die, in which case the metal 75 is expanded uniformly longitudinally and transversely, only a short portion of the metal is broken down at each blow of the top die. In this way the portion forming the bit tends to increase in length rather than in 80 breadth. Other advantages are that this construction permits of a compact device, and that irons of various thickness may be formed without necessitating the changing 85 of dies.

We claim:

1. A pair of dies comprising a bottom die having a breaking down portion for breaking down calking irons and the like, and a top die projecting beyond the edge of the 90 bottom die for bending the unformed portion of the iron out of the longitudinal plane of the formed portion.

2. A pair of dies comprising a bottom die having a breaking down portion for breaking down calking irons and the like, said breaking down portion having a prominence of a length approximately equalling the width of the finished iron for breaking down the bit portion of the iron and a top die projecting beyond the edge of the bottom die for deflecting the unformed portion of the iron from the longitudinal plane of the formed portion of the iron.

3. Relatively movable dies comprising a 105 bottom die having a breaking down portion for breaking down calking irons and the like, said breaking down portion having a prominence of a length approximately equalling the width of the formed portion of the iron, a radius at one end of the prominence to form a corresponding radius at the juncture of the formed and unformed portions of the tool and on one side thereof, and a reciprocable top die having a projecting portion to extend beyond the front edge of the bottom die for bending the unformed portion of the iron out of the longitudinal plane of the formed portion during each 110 blow of the top die.

In testimony whereof we have signed this specification.

LEWIS C. BAYLES.
HOWARD W. MORROW.
